(74) *Attorney, Agent, or Firm* — Rankin, Hill & Clark LLP

(57) **CLAIM**

The ornamental design for a cleaning tool handle, as shown and described.

DESCRIPTION

FIG. 1 is a perspective view of a cleaning tool handle showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The broken lines in the drawings depict portions of the cleaning tool handle that form no part of the claimed design. The broken lines in the drawings showing a cleaning implement removably attached to an end portion of the cleaning tool handle depict environmental subject matter that form no part of the claimed design.

1 Claim, 5 Drawing Sheets
